UNITED STATES PATENT OFFICE

111,048

DESIGN FOR A DISPLAY BOOTH OR SIMILAR ARTICLE

Benjamin E. Levin, Lynn, and Roy A. Winchenbaugh, Boston, Mass.

Application April 30, 1938, Serial No. 76,892

Term of patent 7 years

To all whom it may concern:

Be it known that we, Benjamin E. Levin and Roy A. Winchenbaugh, citizens of the United States, residing at Lynn, in the county of Essex, Commonwealth of Massachusetts, and at Hyde Park, Boston, in the county of Suffolk, Commonwealth of Massachusetts, respectively, have invented a new, original, and ornamental Design for a Display Booth or Similar Article, of which the following is a specification, reference being had to the accompanying drawing, forming a part thereof, wherein Fig. 1 is a perspective view of a display booth showing our new design and Fig. 2 is a top plan view of such booth.

We claim:

The ornamental design for a display booth or similar article, substantially as shown.

BENJAMIN E. LEVIN.
ROY A. WINCHENBAUGH.
